SAUCER HAVING CUP ELEVATING MEANS

Tennyson T. O'Brien, Houston, Tex.

Application March 13, 1951, Serial No. 215,244

1 Claim. (Cl. 65—15)

1

This invention relates to improvements in ceramics and is directed particularly to improvements relating to plates and saucers.

In the use of tea and coffee cups and saucers, and other dishes in which a liquid carrying receptacle is set, some of the contents of the receptacle may be spilled into the plate or saucer so that when the receptacle is lifted drops of liquid will form on the bottom and drip off, frequently on the user, or on the table or floor.

It is an object of the present invention to provide a novel means of avoiding the above described annoying condition by the provision of risers or supports formed on the bottom of a dish or saucer, upon which the liquid carrying receptacle may be stood, so that the bottom thereof will not rest in any liquid which may be spilled into the underlying dish.

Another object is the provision of a means as above set forth whereby such risers, or supports, may be readily cleansed and kept sanitary by reason of their being separable for cleaning, from the plate or saucer.

The invention will be best understood from a consideration of the following detailed description taken in connection with the accompanying drawing, with the understanding, however, that the invention is not to be limited to the exact details of construction shown and described since obvious modifications will occur to a person skilled in the art.

In the drawing:

Figure 1 is a view in top plan of a dish, such as a saucer, showing in association therewith an assembly of risers constructed in accordance with the present invention.

Figure 2 is a sectional view taken substantially on the line 2—2 of Figure 1.

Figure 3 is a view in perspective of one of the risers.

Figure 4 is a sectional view corresponding to Figure 2, showing another embodiment of the invention.

Referring now more particularly to the drawing the numeral 10 generally designates any conventional type of dish in which a receptacle may be set, such, for example, as a saucer designed to receive a cup, shown in dotted outline and designated 12. Such a dish commonly has a central, annular shoulder 14, provided to keep the receptacle 12 from sliding from position. Such shoulder is utilized in carrying out the present invention.

In accordance with the present invention there are provided for disposition in an assembly with-

2

in the central area of the dish defined by the shoulder, a number of risers, each of which is generally designated 16. Since they are all of the same form, a description of one will suffice for all.

Each riser comprises a flat arm 17, which is joined at one end to the face of a flat, rectangular head or block 18.

As shown one longitudinal edge 19 is in the same plane as a side edge 20 of the head 18, such edge 20 comprising the bottom of the head and the edge 19 comprising the bottom of the arm.

The arm is perpendicular to the flat side face of the head, to which it is joined and is positioned midway between the vertical sides 21 of the head. The top edge 22 of the arm is well below the top edge 23 of the head. Thus it will be seen that the riser is in the form of a T lying flat on the bottom of the saucer, the edge surfaces 19 and 20 forming the bottom and the back, or outer side, of the head abutting the shoulder 14.

As shown in Figure 1, by disposing a number of the risers within the circular area defined by the shoulder 14, with the free ends of the arms directed radially toward the center of the area, a cup may be placed on the arms, as shown in Figure 2 and will be kept elevated above the saucer bottom, so that it cannot get in any liquid which may have been spilled in the saucer.

After using the risers they can be removed from the saucer or plate and thoroughly cleansed. Being removable from the plate, the plate may also be cleaned thoroughly as there are no corners or angles which would be difficult to clean.

Figure 4 illustrates another embodiment wherein the risers are made as an integral part of the dish.

As shown, the dish is designated 10a and the risers are generally designated 16a.

In this second embodiment the risers are applied, or fixed, to the material of the dish before firing. The elevators have the bottom edges of the arm 17a and head 18a fixed by the firing operation to the body of the dish. Thus the risers become an inseparable part of the dish.

While in the second embodiment the risers are an integral part of the dish, the sanitary features are retained by reason of the fact that all the corners and angles are rounded so that cleaning is made easy.

I claim:

As a new article of manufacture, a dish having a central circular area defined by an upstanding shoulder, and a plurality of substantially T-shaped members spaced a quarter distance apart

within said area with the heads of the members abutting said shoulder and the arms thereof directed radially toward the center of the area, said members being formed integrally with the dish, the head and arm parts of each of the members being flat and disposed on edge and the head projecting a substantial distance above its arm and said shoulder.

TENNYSON T. O'BRIEN.
